INVENTOR:

James E. Brundage,
BY E. R. Brown,

UNITED STATES PATENT OFFICE.

JAMES E. BRUNDAGE, OF BROOKLYN, NEW YORK, ASSIGNOR TO HIMSELF AND HEWLETT VALENTINE, OF SAME PLACE.

BOTTLE-STOPPER FASTENER.

SPECIFICATION forming part of Letters Patent No. 224,327, dated February 10, 1880.

Application filed December 10, 1879.

To all whom it may concern:

Be it known that I, JAMES E. BRUNDAGE, of Brooklyn, in the county of Kings and State of New York, have invented a new and useful

5 Improvement in Bottle-Stopper Fastenings; and I do hereby declare that the following is a full, clear, and exact description thereof.

My invention relates to a means for securing the stoppers in bottles such as are used 10 for holding cider and various aerated liquids. For this purpose different mechanical devices have been employed working entirely on the outside of the neck of the bottle.

The object of my invention is to provide a 15 cheap, simple, safe, and reliable fastening working on the inside of the neck; and the invention consists in a loop or strap having its ends formed into hooks and engaging with recesses and abutments in the interior of the 20 neck of the bottle, while the top of the loop engages with the top of the stopper, whereby both stopper and loop are securely held and accidental displacement is rendered impossi-ble.

25 In the accompanying drawings, Figure 1 represents a side view of a bottle illustrating my invention. Fig. 2 is a vertical section. Fig. 3 is a perspective view of the fastening-loop. Fig. 4 is a top view of the neck of the 30 bottle.

The bottle A may have the outside of the neck of the usual or any suitable form. On the interior surface of the neck of the bottle are two recesses, a a , diametrically opposite 35 each other. Each recess is of a width and depth corresponding with the thickness of the wire composing the loop, and is in the form of an arc of a circle. The portion within said arc forms an abutment, a^2 . These recesses and 40 abutments are formed while the glass is in a plastic state by means of an expanding-tool of suitable description.

The loop or strap (see Fig. 3) consists of a wire, B, bent so as to form three sides of a 45 square or rectangular figure, and having its

ends curved to form hooks b b . The curve of each hook b corresponds with the curve of the recess a in the neck of the bottle, so that said hooks work nicely in said recesses.

In using this fastening, the ends of the hooks 50 b are inserted in the tops of the recesses a , with the loop in the horizontal position shown in dotted lines in Fig. 2, and the loop is then moved to the vertical position shown in full lines in Figs. 1 and 2, so as to embrace the 55 stopper c and hold it securely in place.

The loop may be placed in the first position either before or after the stopper is inserted.

I am aware that patents have been granted for stopper-fastenings consisting of swinging 60 loops having their bearings on rings outside of the necks.

I am also aware that a patent has been granted for a stopper-fastening consisting of a loop having its ends turned inward toward 65 each other and engaging with sockets on the outside of the neck.

My invention possesses advantages over those, inasmuch as it is impossible for the stopper to escape or be withdrawn while the 70 loop is in position over the top of the stopper without breaking the bottle, because the ends or vertical portions of the loop, being inside the neck, cannot spring outward laterally; and as the hooks b fit nicely in and correspond with 75 the shape of the recesses a and engage with the abutments a^2 , the wire cannot be straightened out by any force which can be brought to bear upon them.

What I claim as new, and desire to secure 80 by Letters Patent, is—

A bottle-stopper fastening consisting of a loop or strap having its ends curved and engaging with recesses and abutments in the interior of the neck of a bottle, substantially as 85 and for the purpose herein described.

JAMES E. BRUNDAGE.
